(57) CLAIM

The ornamental design for a gun body for a spray gun, as shown and described.

DESCRIPTION

FIG. 1 is a perspective view of a gun body for a spray gun showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof in use.

The broken line showing of the spray gun in FIG. 8 illustrates the environment of the claimed design and form no part thereof. The remaining broken lines in the drawings illustrate portions of the gun body for a spray gun and form no part of the claimed design.
